UNITED STATES PATENT OFFICE.

JOHN W. ANDERSON, OF CHICAGO, ILLINOIS, ASSIGNOR TO CORBER COMPANY, OF AURORA, ILLINOIS, A CORPORATION OF ILLINOIS.

CONCEALED HINGE.

Application filed February 9, 1925. Serial No. 8,029.

My invention relates to concealed hinges of the type used on automobile bodies, and it consists in the combinations, constructions, and arrangements herein described and 5 claimed.

An object of my invention is to provide a concealed hinge having a maximum clearance as compared with its size. I accomplish this object by locating the pintle or 10 axis of the hinge at the extreme corner of the hinge box. The hinge box on the side in which the axis is located is also very thin, thus giving further swing to the hinge arm.

15 A further object of my invention is to provide a hinge of the type described having a separable arm which may be readily taken apart so that the door may be readily removed or replaced.

20 A further object of my invention is to provide a hinge of relatively light weight, but which is strong and durable owing to the fact that the pivots of the hinge are spaced far apart to provide a long bearing.

25 Other objects and advantages will appear in the following specification, and the novel features of the invention will be particularly pointed out in the appended claims.

30 My invention is illustrated in the accompanying drawing, forming part of this application, in which

Figure 1 is a transverse section through the hinge and through the door frame and door,

35 Figure 2 is a face view of the hinge showing the hinge arm in its open position,

Figure 3 is a sectional view of a portion of the separable hinge arm,

40 Figure 4 is a section along the line 4—4 of Figure 3, and

Figure 5 is a section along the line 5—5 of Figure 2.

45 The hinge which forms the subject of the present invention is an improvement over that set forth in prior applications Serial No. 464,195 of April 25, 1921 and No. 508,805, of October 19, 1921.

50 In carrying out my invention, I provide a hinge box portion which as will be seen from Figure 2 is U shaped in cross-section, having a central portion 1 and side portions 2. Integral with the side portions 2 are laterally extending flanges 3 provided with screw

openings 4. The side members 2 have near their outer edges a reenforcement 2^a which 55 consists merely of a thickening of the plate and in this reenforcement is a groove 5 which constitutes part of the journal for the pivot members of the hinge. Adjacent to this groove is an integral stud 6 the purpose of 60 which will be explained later. The outside of the members 2 from one edge of the flange 3 to the opposite diagonal corner is made thinner so as to provide a shoulder along the line 7.

65 The hinge arm proper consists of an L shaped body portion 8 having cutaway portions 9 to clear the thickened portions 2^a of the walls 2 of the box and being provided with pintle members 10, which are arranged 70 to bear in the groove 5.

As will be seen from Figure 1 there is a shoulder 11 on each side of the arm which is arranged to engage the portion 2^b of the thickened portion 2^a, this portion 2^b acting 75 as a stop for limiting the movement of the arm.

The opposite end of the L shaped arm 8 has a cutaway portion on each side thereof as shown at 12. At one end of the cutaway portion is a V shaped shoulder 13, while at the other end are cylindrical lugs 14. That portion 15 of the arm between the cutaway portions 12 is thickened as will be seen from Figures 3 and 4, and through this thickened 85 portion a screw 16 extends, the bore in which the screw is located being threaded and the end of the screw 16^a being upset so as to prevent the withdrawal of the screw, while permitting a retraction thereof within limits.

90 The retaining plate which is secured to the door 26 is shown at 17 and is provided with the usual screw openings 18. It will be observed that this plate has a central opening 19 and that the corners of this opening are 95 flanges 20 having at their ends V shaped recesses 21. These flanges have sockets 22 which are arranged to receive the cylindrical studs 14. Between the flanges 20 is a recess 23 which is designed to straddle the screw 100 in the manner hereinafter explained.

Forming part of the hinge box is a triangular shaped cover portion 24 which is made preferably of thin stamped metal, and which is provided with openings 25 as shown 105 in the drawings.

In assembling the device the L shaped arm 8 is passed up through the U shaped box portion and the pintle portions 10 are placed in the grooves 5. The light metal cover portion is now placed in position, the studs 6 passing through the openings 25 and being riveted so as to hold the cover portion 24 securely. It will be observed that the inner corner of this cover portion forms part of the journal for the hinge pintles 10. The edge of the cover portion rests on the shoulder 7 of the side members 2, so that the member 24 is held rigidly in position when the lugs 6 are upset or riveted.

In connecting the arm to the plate 17, the arm is tilted slightly and then thrust into the central opening 19, the V shaped shoulders 13 entering the V shaped recesses 21 of the flanges 20, and then when the arm is tilted back into normal position the cylindrical lugs 14 enter the sockets 22. The screw 16 is now tightened. The end of the screw engages the plate 17 in the wall of the opening 19. This holds the assembled arm in absolutely rigid position, for it will be observed that the entrance of the shoulders 13 into the sockets 21 prevents movements at these points, while the entrance of the cylindrical lugs 14 into the sockets 22 prevents further movement, as long as the cylindrical lugs are held in the sockets 22. This last is accomplished by the screw 16 which not only holds the two together by means of its head, but by bearing on the plate at the inner wall of the opening 19, it also holds it from any movement. The result is that I have provided a quickly detachable arm for the hinge which can be taken apart by a few turns of the screw, or which can be secured rigidly by a few turns.

From the foregoing description of the various parts of the device, the operation thereof may be readily understood. By locating the pivotal points of the hinge at the extreme corner of the box, I obtain the maximum throw or clearance which it is possible to obtain from any box of given size. Furthermore, the wall of the box toward which the hinge swings when it is being opened, is comparatively thin being a thin sheet of metal. This again gives the arm a further throw. The stamped metal cover portion, as has been observed, not only forms a means for keeping out dust but it acts as part of the journal of the hinge and thus has a double function. But aside from this, it reduces the weight of the hinge without impairing the strength.

The ease with which the arm portions are detached, or secured together forms an important feature of the hinge. It obviates the necessity of taking the box apart or any portion thereof, to remove the hinge from its bearing. It permits the hinge arm to be swung outwardly in a position where the re-

taining screw is easily accessible so that a door can be quickly removed or replaced as desired.

I claim:

1. A hinge of the concealed type comprising a U shaped box member having bearing grooves at certain outer corners thereof, a cover portion for said grooves, an L shaped hinge arm having pintle members arranged to enter said bearing grooves, and a door-retaining plate secured to said L shaped arm, said arm being arranged to swing into and be concealed by said box when the hinge is closed.

2. A hinge of the concealed type comprising a U shaped box member, a cover portion for forming with said U shaped member, a rectangular box having an open side, said U shaped member having bearing grooves in certain corners thereof, the portion of the cover adjacent said bearing grooves constituting part of the bearing, an L shaped arm having pintle members disposed at one end and arranged to enter between said bearing grooves, and the cover at a corner thereof, a removable door-retaining plate carried by the other end of said L shaped arm, said arm being arranged to enter said box when moved on said pintles so as to be entirely concealed therein.

3. A hinge of the concealed type comprising a rectangular box portion having bearing grooves at the extreme ends of certain corners, an L-shaped hinge arm pivotally mounted in said bearing grooves, said L-shaped hinge arm comprising a pair of separable members, one of said members having spaced apart sockets and the other having spaced apart shoulders, certain of said shoulders being arranged to enter certain of said sockets when the parts are tilted out of normal position, and the other shoulders being arranged to enter the remaining sockets when the parts are swung into normal position, and means for retaining the arm portions in their normal locked positions.

4. A hinge of the concealed type comprising a rectangular box portion having bearing grooves at the extreme ends of certain corners, an L-shaped hinge arm pivotally mounted in said bearing grooves, said L-shaped hinge arm comprising a pair of separable members, one of said members having spaced apart sockets and the other having spaced apart shoulders, certain of said shoulders being arranged to enter certain of said sockets when the parts are tilted out of normal position, and the other shoulders being arranged to enter the remaining sockets when the parts are swung into normal position, and a screw carried by one arm portion and arranged to bear on the other arm portion for maintaining the arm portions in their normal locked position.

5. A hinge of the concealed type comprising a U-shaped rectangular box portion having three open sides, said box having bearing grooves at the extreme ends of certain corners adjacent to two of the open sides, an L-shaped hinge arm having pivot members arranged to enter said bearing grooves and being adapted to swing through one of said open sides, and a rectangular cover plate for the other two sides, the corner of said cover plate serving as means for retaining the pivot portions in position. 35
- 10 6. A hinge of the concealed type comprising a rectangular box having bearing grooves at the extreme ends of certain corners, an L-shaped hinge arm formed of two separable arm members one of said arm members being provided at one end with pivot portions arranged to enter said bearing grooves, a cover member for said box cooperating with the grooved portions of said box to provide bearings for said pivot portions, means secured to said box for retaining said pivot portions within said 40
